UNITED STATES PATENT OFFICE.

SOPHIE STIEBEL, OF PHILADELPHIA, PENNSYLVANIA.

DESIGN FOR A POCKET-BOOK CARRIER.

SPECIFICATION forming part of Design No. 27,529, dated August 17, 1897.

Application filed June 16, 1897. Serial No. 641,072. Term of patent 7 years.

To all whom it may concern.

Be it known that I, SOPHIE STIEBEL, a citizen of the United States, and a resident of the city and county of Philadelphia, State of Pennsylvania, have invented and produced a new and original Design for Pocket-Book Carriers, of which the following is a specification, reference being had to the accompanying drawing, forming part thereof, in which the figure is a perspective view of my pocket-book carrier.

The leading feature of my design lies in the particular form and arrangement of the encircling bands for the finger and for the pocket-book.

A is the encircling band for the finger. This band is circular in form, as shown, and may

carry a jewel B, or be ornamented in any other suitable manner.

C is the encircling band for the pocket-book. This band is elliptic in form and is placed at right angles to the band A, to which it is united by fillets D. This band may be engraved in any suitable manner.

Having thus described my invention, I claim as new and desire to secure by Letters Patent—

The design for a pocket-book carrier as herein shown and described.

SOPHIE STIEBEL.
